US0D1039322S

(12) **United States Design Patent** (10) Patent No.: **US D1,039,322 S**
(45) Date of Patent: ** Aug. 20, 2024

(54) **COOKING APPLIANCE**

(71) Applicant: **LG Electronics Inc.**, Seoul (KR)
(72) Inventors: **Jaehung Chun**, Seoul (KR); **Taejo Kim**, Seoul (KR); **Jonghak Lee**, Seoul (KR); **Goeun Joo**, Seoul (KR); **Junghoon Lee**, Seoul (KR)
(73) Assignee: **LG ELECTRONICS INC.**, Seoul (KR)
(**) Term: **15 Years**
(21) Appl. No.: **35/519,004**
(22) Filed: **Nov. 17, 2022**

(80) **Hague Agreement Data**

Int. Filing Date: **Nov. 17, 2022**
Int. Reg. No.: **DM/225325**
Int. Reg. Date: **Nov. 17, 2022**
Int. Reg. Pub. Date: **Nov. 17, 2023**

(30) **Foreign Application Priority Data**

May 17, 2022 (KR) 30-2022-0019584

(57) **CLAIM**

The ornamental design for a cooking appliance, as shown and described.

DESCRIPTION

1. Cooking appliance

1.1 : Perspective
1.2 : Front
1.3 : Back
1.4 : Left
1.5 : Right
1.6 : Top
1.7 : Bottom
1.8 : Top view 2

The broken lines depict portions of cooking appliance that form no part of the claimed design; reproduction 1.8 is a top view showing the state of use that the display has been operated; the display shown in reproduction 1.8 and not shown in any of the other views is unclaimed subject matter that appears only during the use state. This design is for a Cooking appliance that can stir-fry, roast, deep-fry, boil, wok-hei, etc. As shown in reproduction 1.8, the upper half-circle part on the top of the cover is the display part, and

(Continued)

the lower half-circle part is made of transparent material, so that the user can check the cooking status of the food at the inside pot.

1 Claim, 8 Drawing Sheets
